Primary Examiner — Llorellys Martinez(74) *Attorney, Agent, or Firm* — Cook Alex Ltd.(57) **CLAIM**

The ornamental design for a grid tee for suspended ceiling, as shown and described.

DESCRIPTION

FIG. 1 is a perspective view of a grid tee for a suspended ceiling according to the present application;

FIG. 2 is a left end view of the grid tee for suspended ceiling, the right end view being a mirror image thereof;

FIG. 3 is a front view of the grid tee for suspended ceiling, the rear view being a mirror image thereof;

FIG. 4 is a top view of the grid tee for suspended ceiling; and,

FIG. 5 is a bottom view of the grid tee for suspended ceiling. The grid tee for suspended ceiling is shown with a symbolic break in its length. The appearance of any portion of the grid tee for suspended ceiling between the break lines forms no part of the claimed design.
